UNITED STATES PATENT OFFICE.

JULIUS STEINER, OF ST. LOUIS, MISSOURI.

MOSQUITO-BAR SUPPORTER.

SPECIFICATION forming part of Letters Patent No. 241,829, dated May 24, 1881.

Application filed June 2, 1879.

To all whom it may concern:

Be it known that I, JULIUS STEINER, of the city of St. Louis, in the State of Missouri, have invented certain Improvements in Mosquito-Bar Supporters; and I do hereby declare the following to be a full, clear, and exact description of the same, reference being had to the accompanying drawings, and to the letters of reference marked thereon.

10 The purpose of this invention is to form a mosquito-bar supporter which can be adjusted to any desired height, and which, when not in use, can be shut together and turned away out of sight; and this invention consists in the construction and arrangement of parts, all as will hereinafter more fully appear.

In the drawings, Figure 1 is a perspective view illustrating my invention. Fig. 2 is a side view, partly in section. Fig. 3 is a detail view 20 of modified form of supporter.

A is a hollow fixed guide, secured by brackets a or otherwise to the back of the head-board B of the bedstead. Inside of this guide slides the bar or rod C, which has a curved top, 25 C', in which is hinged, at d , the overhanging arm D, to which is attached the frame of the mosquito-bar, and said arm D is held in its upward or extended position by a curved brace,

E, pivoted to said arm at e , and having a shoulder, e' , which engages against the lower 30 side of a slot, e^2 , in the straight portion of the bar or rod C. The shoulder e' is held from disengagement by a coiled spring, e^3 , in said bar or rod C.

As shown in Figs. 1 and 2, the rod C and 35 guide A both turn in a top bracket, a , and on a step or bearing, a' , and they are secured at any position to which they are turned by means of a set-screw, a^2 . The bar C is held at any required height by its clamping-screw c , which 40 passes through a slot in the slide of the housing A, and clamps against the side of the same to hold the rod C fixedly at any desired height.

When not in use the device can be turned around and folded together, as clearly indicated 45 in Fig. 1.

I claim as my invention—

The combination, in a mosquito - bar supporter, of the hinged arm D and brace E, having a shoulder, e' , with the rod C, having a 50 slot, e^2 , and spring e^3 , as and for the purpose set forth.

JULIUS STEINER.
